WRAPPING PAPER

Elizabeth Nightingale Graham, New York, N. Y.

Application December 13, 1955, Serial No. 39,312

Term of patent 14 years

(Cl. D59—2)

Fig. 1.

Fig. 1

Figure 1 is a plan view of a wrapping paper showing my new design. The width of the wrapping paper represents the full width of the design unit, and its length is indicated by the dot and dash lines extending across it.

Figure 2 is an enlarged view of a fragment of the design unit outlined in dot and dash lines on Figure 1.

I claim:

The ornamental design for a wrapping paper, substantially as shown and described.
